(57) **CLAIM**

The ornamental design for a descent device, as shown and described.

DESCRIPTION

FIG. 1 is a top, front, right perspective view of a descent device showing our new design;

FIG. 2 is a top view thereof;

FIG. 3 is a bottom view thereof;

FIG. 4 is an enlarged left side view thereof, the right side view being a mirror image thereof;

FIG. 5 is a rear view thereof;

FIG. 6 is a top, front, right perspective view of the descent device of FIGS. 1-5 in an open position; and,

FIG. 7 is a top, front, right perspective view of the descent device of FIGS. 1-5 in a second open position.

The broken lines are for environmental purposes only and form no part of the claimed design.
